US0D1046906S

(12) **United States Design Patent** (10) Patent No.: **US D1,046,906 S**
 Liu (45) Date of Patent: ** Oct. 15, 2024

(54) **DISPLAY SCREEN WITH GRAPHICAL USER INTERFACE**

(71) Applicant: **Tianjin Yolin Technology Co., Ltd.**,
 Tianjin (CN)

(72) Inventor: **Jingzhao Liu**, Tianjin (CN)

(73) Assignee: **Tianjin Yolin Technology Co., Ltd.**,
 Tianjin (CN)

(**) Term: **15 Years**

(21) Appl. No.: **29/886,465**

(22) Filed: **Mar. 8, 2023**

(51) LOC (14) Cl. **14-04**

(52) U.S. Cl.
 USPC **D14/486**

(58) **Field of Classification Search**

CLAIM

The ornamental design for a display screen with graphical user interface as shown and described.

DESCRIPTION

The FIGURE is a front view of a display screen with graphical user interface, showing my new design.

The broken lines showing numbers and portions of the graphical user interface form no part of the claimed design.

1 Claim, 1 Drawing Sheet
